UNITED STATES PATENT OFFICE.

JOSEPH CRITELLI, OF JONESPOINT, NEW YORK.

AUTOMOBILE WATER BAG.

Application filed July 22, 1926. Serial No. 124,124.

This invention relates to water bags and more particularly to a container used by motorists for a reserve supply of water to be utilized in the cooling system of a conventional automobile.

Heretofore, it has often been necessary to travel quite a distance to procure water for the radiator of an automobile after the same has made a trip of considerable mileage and 10 has become overheated. This condition is very detrimental to the smooth operation of a motor car and hence should be avoided. In the past, if a reserve supply was taken along by a motorist on a long trip, it had to be transported in a bulky and awkward container, taking up considerable space. Moreover, it was clumsy and hard to handle during the refilling of the drained radiator.

One of the objects of the invention is to 20 provide a bag that is waterproof and capable of retaining a supply of water for an extended period.

Another object is in the provision of a 25 novel locking means whereby a positively water-tight joint is secured.

A further aim is to provide a collapsible water bag of substantially unitary construction, capable of being compactly and flatly folded when not in use so as to take up 30 little space.

These and other objects, which will become apparent as the description progresses, are accomplished by the novel construction, combination and arrangement of parts, hereinafter described and illustrated in the accompanying drawing, forming a material part of this invention, and in which:—

Figure 1 is a side view showing the device in position to empty its contents into an 40 automobile radiator.

Figure 2 is a vertical sectional view taken on line 2—2 of Figure 3.

Figure 3 is a side elevational view of the device shown as unfilled.

Figure 4 is an end view of the same.

Figure 5 is a perspective view illustrating the bag in a folded position adapted to be conveniently and easily carried without loss of space.

In the drawing, the numeral 10 designates 50 the walls of a bag, made of any preferred water-proof fabric, having its lower and one of its side edges inturned and folded at 11 to present a water-tight seam, the fabric being secured by stitches 12.

The top edge of one of the side walls 10

is folded outwardly twice upon itself at 13 and is secured by stitches 14.

The opposite top edge is folded inwardly at 15 and back upon itself at 16 to present 60 an element 17 on the outer side of the bag.

Riveted at 18 to the element 17 is a thin, narrow, metal strip 19, the top edge of which is raised and looped at spaced intervals to present a plurality of hinges 20 in 65 which is secured a rod 21.

Hinged intermediate the elements 20 on the rod 21, is the upwardly curled portions 22 on a second metal plate 23 bent at right angles to seat on the upper edge of the bag 70 and attached to the inner folds 15 and 16 by rivets 24.

Mounted on the rod 21 is a pair of coiled springs 25 having their opposite ends pressing on the plates 19 and 23 at 26 and 27 respectively to normally hold the plate 23 75 closely adjacent the wall.

As may be seen in Figure 2, the dotted lines show the plate 23 and the folds 15 and 16 to which the plate is secured in an open 80 position. When the bag 10 is filled with a reserve supply of water, the folded top edges are brought together into close relation and then the folds 15 and 16 and the plate 23 is snapped down over the folds 13 to fold a 85 water-tight locking means.

It very often occurs, that on long trips in an automobile, the driver finds that his radiator doesn't contain any more water and that to continue with the motor in that condition would be detrimental to the car. If he happens to be in a sparsely populated district, it might be necessary that he walks several miles to get a supply of water. This difficulty may be overcome as shown in Figure 1, water from the bag 10 may be poured 95 through the stem 27 into the conventional radiator 28 mounted at the front of the motor vehicle.

When the container is not in use, it may 100 be neatly and compactly folded for storage as seen in Figure 5, taking up very little space.

From the foregoing, it may be seen that a water-proof container for carrying a reserve supply of radiator water has been disclosed, that is not only useful to motorists, but also quite essential and necessary.

The foregoing is not to be interpreted in a limiting sense, it is simply and purely descriptive, as, obviously changes in construction, such as sizes, shapes and proportions,

may be made without departing from the spirit or scope of the appended claim.

Having thus described my invention, what I claim as new and desire to secure by Letters Patent, is:—

A water-proof bag comprising a pair of integral side walls, water-tight seams on the lower and one of the side edges of said walls, reenforcing folds on the top edges of said

side walls, a metal plate fixed on one of said folds, a second plate capable of overlapping the other of said reenforcing folds, hinged to said first plate and means contacting both of said plates to normally hold the same in a closed position.

In witness whereof I have affixed my signature:

JOSEPH CRITELLI.
